CARBURETOR OF THE VACUUM CONTROLLED TYPE

Harry W. McClain, Long Beach, Calif.

Application January 16, 1953, Serial No. 331,668

4 Claims. (Cl. 261—44)

This invention relates to a carburetor of the vacuum controlled type in which a piston within the cylinder portion of the carburetor is caused to move due to a vacuum above the piston, and the movement of this piston in turn controls a fuel needle valve to admit fuel into the air stream flowing into the engine.

An object of my invention is to provide a novel carburetor of the character stated which is simple in construction and effective in operation.

Another object of my invention is to provide a novel carburetor of the character stated in which the operating piston in the carburetor has an air control valve or cap thereon which controls the flow of air into the intake pipe of the engine.

Another feature of my invention is to provide a novel means of automatically compensating for the different air pressures at higher altitudes whereby the carburetor will operate effectively at high altitudes as well as at sea level.

Another feature of my invention is to provide a simple and effective means to prevent excessive and rapid movement of the actuating piston in the cylinder portion of the carburetor, this being accomplished by an outside air bleed.

Other objects, advantages and features of invention may appear from the accompanying drawing, the subjoined detailed description and the appended claims.

In the drawing:

Figure 1 is a longitudinal sectional view of the preferred form of my carburetor.

Figure 2 is a sectional view taken on line 2—2 of Figure 1.

Figure 3 is a longitudinal sectional view of a modified form of my carburetor.

Figure 4 is a sectional view taken on line 4—4 of Figure 3.

Figure 5 is a fragmentary side elevation of the piston mounted within my carburetor.

Referring more particularly to the drawing, and especially to the preferred form of my invention shown in Figures 1 and 2, in this embodiment an intake pipe 1 is provided with the usual mounting flange 2 so that the carburetor may be attached to the engine intake manifold 3. The pipe 1 opens into, also depends from, and is preferably an integral part of a cylinder 4 which is considerably larger in diameter than the pipe 1. A throttle valve 5 of usual and well known design is mounted in the pipe 1 and the position of this throttle valve determines the amount of air and entrained fuel which flows into the engine.

An air intake pipe 6 extends into the side of the cylinder 4 and this pipe admits air under atmospheric pressure into the carburetor. The reciprocation of the pistons in the engine creates a vacuum and this vacuum is highest when the throttle valve 5 is closed. As the valve 5 swings open the vacuum below the valve 5 is transferred to the space 7 above the throttle valve. As vacuum is created in space 7 this vacuum is filled by the air flowing in through the pipe 6. To satisfy and fill the vacuum in the

2

space 7, I provide a cup or valve 8 which is caused to rise or fall, and thus vary the amount of air admitted to the space 7 through the intake pipe 6. As the engine requires more air, the valve or cap 8 is caused to move upwardly permitting more air to flow into the pipe 1 through the intake pipe 6 by the following construction:

A transverse wall 9 is provided in the cylinder 4 above the air intake pipe 6. A tube 10 rises from the cup or valve 8 and this tube also extends through the top of the cylinder 4. It will thus be evident that the tube 10 has two supports or bearing guides, one in the transverse wall 9 and the other in the top wall of the cylinder 4. These two bearings preferably consist of metal rings 11 and 12 which accurately guide the tube and effectively support and guide the piston 13 which is fixedly attached to the tube 10 above the transverse wall 9. This piston 13 is thus accurately guided and prevented from dragging against the wall of the cylinder 4. There is thus provided a chamber 14 above the piston 13 and a second chamber 15 below the piston 13.

A fuel chamber 16 is mounted on the side of the cylinder 4 and the usual float 17 is mounted within the float chamber for the purpose of maintaining a constant fuel level therein. A fuel intake pipe 18 extends from the fuel chamber 16 into the pipe 1, and then extends upwardly at an elbow to a metering jet 19. A tapered needle valve 20 extends into the metering jet 19 and this needle is attached to a rod 21 which is threaded into the upper end of the tube 19. This threaded coupling permits the needle 20 to be raised or lowered relative to the metering jet 19 to adjust proper fuel flow at different speeds. A port 22 is provided through the wall of the tube 10 above the piston 13, thus enabling the vacuum present in the chamber 7 to be transferred to the chamber 14. These two chambers thus have the same amount of vacuum at all times.

To prevent the piston 13 from violently moving upwardly or downwardly, I provide an air bleed 23 which can be manually adjusted by the screw 24, thus bleeding atmospheric air into the chamber 15 which acts as a check to prevent the piston 13 from rapid movement. Any movement of the throttle 5 towards an opening position will tend to increase the vacuum in the chamber 7. This increased vacuum is then transferred to the chamber 14. The piston 13 will thereupon move upwardly which carries the needle 20 upwardly, opening the fuel metering jet 19 to admit fuel into the incoming air which is moving through the intake pipe 6, thence around the bottom of the cup valve 8, and thence downwardly through the pipe 1 and into the engine.

As long as air is coming into the chamber 7 it will satisfy the vacuum therein and, consequently, the position of the piston 13 remains constant. This condition continues until the throttle valve 5 is either opened a greater amount or closed. If it is opened a greater amount the piston 13 moves upwardly, thus moving the cup valve 8 upwardly and admitting more air. If the throttle valve 5 closes, the vacuum in the chamber 7 decreases and the piston 13 drops to the position shown in Figure 1.

A choke construction consists of a tube 25 which extends downwardly in the fuel chamber 16 and is attached at its lower end to the fuel intake pipe 18. A needle valve 26 within the tube 25 rests on a seat at its lower end to normally close the opening into the tube 25. When the needle valve 26 is raised manually by means of the bell crank 27 fuel will be admitted to the tube 25 and this fuel rises in the tube and passes through the duct 28 into the intake pipe 1 at approximately the same level as the metering jet 19.

An altitude compensator consists of a pipe 29 which extends from the top of the fuel chamber 16 and thence into the chamber 14 through the side wall of the cylinder

4. Air flows through the pipe 29 constantly while the carburetor is in operation due to the fact that the chamber 14 is under a partial vacuum, as previously described. An air bleed 30 is provided in the top of the fuel chamber 16 and the size of the port in this air bleed is such that at sea level enough air enters the bleed 30 to maintain atmospheric pressure on top of the fuel in the fuel chamber 16. At higher altitudes, due to less air pressure, the space above the fuel will be more rapidly evacuated by the engine. Consequently, there will be less pressure on the fuel and, as a result, less fuel will be moved to the fuel jet 19, thus providing a leaner mixture at higher altitudes.

In the modification, shown in Figures 3, 4 and 5, the intake pipe 35 extends into the side of the cylinder 36, substantially as shown. An air intake pipe 37 extends into the side of the cylinder 36 opposite the pipe 35. A piston 38 is reciprocally mounted in the cylinder 36 and a skirt 39 extends downwardly from the piston 38 and this skirt has an opening 40 in the side thereof, which opening faces towards the air intake pipe 37. A conduit 41 extends from the top of the intake pipe 35 and thence into the upper part of the cylinder 36 so as to evacuate the upper chamber 42 within the cylinder and above the piston 38.

A tube 43 extends vertically through the piston 38 and through the top wall of the cylinder 36. The lower end of this tube extends into a dash pot 44 which is mounted below the cylinder 36. The tube 43 closely fits the dash pot and oil is provided in this pot as is usual and the oil bleeds through a port 45, thus restricting the movement of the piston 38, particularly in an upward direction. A check valve 46 is also provided in the bottom of the tube 43 and this check valve opens when the piston 38 drops. A needle valve 47 controls the opening of the port 45 and this needle valve extends upwardly through the top of the tube 43. A fuel chamber 48 is positioned at one side of the cylinder 36 and a fuel supply pipe 49 extends into the air intake pipe 35 and at the lower edge of this pipe so that as the air enters from the intake pipe 37 the air will pass across the pipe 49 and carry fuel into the engine.

A needle valve 50 is secured at its upper end to an arm 51 which extends horizontally from the tube 43 and, consequently, the needle valve 50 is raised and lowered as the piston 38 moves. The same altitude control is provided, as previously described, consisting of the pipe 52 which is the same as the pipe 29 previously described, and also the air bleed 53, which is the same as the air bleed 30 previously described. The operation of this carburetor is the same as previously described in that the piston 38 rises and falls with the amount of vacuum created in the chamber 54 above the throttle valve 55.

Having described my invention, I claim:

1. A carburetor comprising a cylinder, a pipe depending from the cylinder, a throttle valve in the pipe, an air intake pipe extending into the cylinder, said cylinder having a chamber therein into which said pipe opens and said air intake pipe extends, a transverse wall in the cylinder defining the top of said chamber, a piston in said cylinder, means on the piston movable with relation to said pipe to control the flow of air into said pipe, a fuel chamber, a fuel pipe extending from the fuel chamber into said first named pipe, and a needle valve projecting from the piston and extending into the fuel pipe to control fuel flow from the fuel pipe, said cylinder having a chamber therein above the piston, and conduit means open to said first named pipe and opening into the last named chamber to evacuate the last named chamber and cause the piston to rise in the last named chamber, an altitude compensator comprising a pipe extending from the top of said fuel chamber and into the last named chamber, said fuel chamber having an air bleed port therein extending into the top thereof.

2. A carburetor comprising a cylinder, a pipe extending from the cylinder, a throttle valve in the pipe, an air intake pipe extending into the cylinder, said cylinder having a chamber therein into which said pipe opens and said air intake pipe extends, a transverse wall in the cylinder defining the top of said chamber, a piston in said cylinder, a tube extending through the piston, means slidably mounting the tube in the cylinder, a cup on the lower end of the tube of greater diameter than the tube and movable with relation to said first named pipe to control the flow of air into said first named pipe, a fuel chamber, a fuel pipe extending from the fuel chamber into the first named pipe, and a needle valve arranged within the tube and depending therefrom, said needle valve extending into the fuel pipe to control the fuel flow from the fuel pipe, said cylinder having a chamber therein above the piston, said tube having a port therein opening into the chamber to evacuate the last named chamber and cause the piston to rise in the last named chamber.

3. A carburetor comprising a cylinder, a pipe extending from the cylinder, a throttle valve in the pipe, an air intake pipe extending into the cylinder, said cylinder having a chamber therein into which said pipe opens and said air intake pipe extends, a transverse wall in the cylinder defining the top of said chamber, a piston in said cylinder, a tube extending through the piston, means slidably mounting the tube in the cylinder, a cup on the lower end of the tube of greater diameter than the tube and movable with relation to said first named pipe to control the flow of air into said first named pipe, a fuel chamber, a fuel pipe extending from the fuel chamber into the first named pipe, and a needle valve arranged within the tube and depending therefrom, said needle valve extending into the fuel pipe to control the fuel flow from the fuel pipe, said cylinder having a chamber therein above the piston, said tube having a port therein opening into the chamber to evacuate the last named chamber and cause the piston to rise in the last named chamber, an altitude compensator comprising a pipe extending from the top of said fuel chamber and into the last named chamber, said fuel chamber having an air bleed port therein extending into the top thereof.

4. A carburetor comprising a cylinder, a pipe extending from the cylinder, a throttle valve in the pipe, an air intake pipe extending into the cylinder, said cylinder having a chamber therein into which said pipe opens and said air intake pipe extends, a transverse wall in the cylinder defining the top of said chamber, a piston in said cylinder, a tube extending through the piston, means slidably mounting the tube in the cylinder, a cup on the lower end of the tube of greater diameter than the tube and movable with relation to said first named pipe to control the flow of air into said first named pipe, a fuel chamber, a fuel pipe extending from the fuel chamber into the first named pipe, and a needle valve arranged within the tube and depending therefrom, said needle valve extending into the fuel pipe to control the fuel flow from the fuel pipe, said cylinder having a chamber therein above the piston, said tube having a port therein opening into the chamber to evacuate the last named chamber and cause the piston to rise in the last named chamber, said cylinder having a third chamber therein below the piston and an air bleed extending into the third chamber, an altitude compensator comprising a pipe extending from the top of said fuel chamber and into the last named chamber, said fuel chamber having an air bleed port therein extending into the top thereof.
